BREAST FLAP CLAMPING MACHINE

William Neil Bray and Frank Barton, Leicester, England, assignors to United Shoe Machinery Corporation, Borough of Flemington, N. J., a corporation of New Jersey

Application July 26, 1938, Serial No. 221,375
In Great Britain August 6, 1937

16 Claims. (Cl. 12—125)

This invention relates to the manufacture of shoes and is herein illustrated as embodied in a machine for clamping covering flaps against the breasts of attached heels of shoes.

5 In the manufacture of shoes it is common practice, after applying a covering flap to the breast of the attached heel of the shoe by the use of glue or other adhesive, to clamp a rubber pad against the heel breast in order to hold the flap

10 in place until the glue has dried. Machines comprising one or more units each having a replaceable rubber pad such as above referred to have been proposed. The rubber pads should be of suitable shape to conform readily under pres-

15 sure to the breast of the heel, it being customary for one pad to accommodate shoes having heels of slightly different sizes and styles.

In order that the rubber pad may be effectively used in connection with shoes having heels of a 20 wide range of sizes and styles, and in accordance with a feature of this invention, the illustrated machine comprises a support for a shoe, a resilient pad, mechanism for moving the pad heightwise of the shoe against the breast of an attached 25 heel of the shoe to press a laid-up flap against the heel breast, mechanism responsive to heightwise pressure of the pad against the heel breast for moving the pad lengthwise of the shoe against the heel breast, and means for varying the de-

30 gree of lengthwise thrust of the pad against the heel breast with relation to the heightwise thrust of the pad against the heel breast in accordance with the shape of the heel of the shoe.

The illustrated machine is provided with a pair 35 of rubber pads which are moved into engagement with the breast and the rear face, respectively, of the heel of the shoe upon the support, from positions remote from the shoe. The pads are forced into engagement with the heel by treadle-operated mechanism or by power-operated means and are locked in their clamped positions against the heel by a latch until the flap attaching adhesive has dried. If desirable, a plurality of single 40 clamping units may be mounted upon a turret 45 which is rotated step by step and is provided with power-operated means for successively forcing the pads of the different units with additional pressure against the heels of the shoes in the different units while the turret is being moved to 50 its first indexed position.

The various features of the invention will be understood and appreciated from the following detailed description read in connection with the accompanying drawings, in which

55 Fig. 1 is a side elevation, partly broken away,

showing the illustrated machine with a shoe clamped therein;

Fig. 2 is a side elevation, partly in section and partly broken away, of the upper portion of the machine after the shoe has been removed; 5

Fig. 3 is a detail view showing in side elevation a pair of heel clamping pads and mechanism for operating the same;

Fig. 4 is a view showing the mechanism of Fig. 3 as viewed in the direction of arrow IV of Fig. 3; 10

Fig. 5 is a section on line V—V of Fig. 2;

Fig. 6 shows in perspective the carrier for the pad which clamps the flap against the breast of the heel;

Figs. 7 and 8 are side views of mechanism for 15 operating a latch through which the pads are held in clamped relation with the heel;

Fig. 9 is a vertical section of a portion of a turret machine upon which a plurality of clamping units, such as illustrated in Figs. 1 to 8, inclusive, 20 have been mounted;

Fig. 10 is a side view showing in detail a cam of the turret machine through which presser arms of the different units are successively operated; 25

Fig. 11 is a detail view showing a cam of the turret machine for limiting rearward movement of the pad carrier mechanism of the different units.

The illustrated machine is described with reference to clamping covering flaps 20 (Fig. 1), which have been laid upon the breasts of heels 22 of shoes 24 by the use of an adhesive, such for example as hot glue, against the breasts of the heels until the glue has dried. 30

The machine comprises a forwardly extending bracket 26 (Figs. 1 and 2) secured by screws 28 to a pedestal 30 (Fig. 1). Adjustably mounted upon the bracket 26 is a support 32 (Figs. 1, 2, and 5) for the shoe comprising a last pin 34 formed 40 integrally with a yoke 36 engaged by the cone of a last 38 (Fig. 1) upon which the shoe 24 is mounted. The yoke 36 is pivoted on a pin 40 (Figs. 1, 2 and 5) secured to a block 42 which may be moved into different adjusted positions 45 along a flange 44 of the bracket 26. The yoke 36 may be tipped to a slight degree on the pin 40, forward and rearward tipping movement, respectively, of the yoke being limited by a stop face 46 (Fig. 2) on the block 42 and a screw 48 (Figs. 1 and 2) threaded into the block. The block 42 may be secured in different adjusted positions on the bracket 26 by a thumb screw 50 (Figs. 2 and 5) which is threaded into the block. As shown in Fig. 5, the yoke 36 is movable to a slight ex- 55

tent along the pin 40. By tipping and sliding the yoke 36, as above described, upon the block 42, and adjusting the block along the flange 44 of the bracket 26, the operator is enabled to position the shoe to the best advantage relatively to clamping pads 52, 54 which will be described later.

The toe portion of the shoe 24 (Fig. 1) mounted upon the support 32 engages a rubber covered 10 rod 56 (Figs. 1 and 2) secured to the forward end of a flexible metal strip 58 secured by screws (not shown) to a slide 60 movable in a horizontal guideway of a post 62. The post 62 is provided with a recess for receiving a spring-pressed 15 plunger 64 (Fig. 2) arranged to engage one of three recesses 66 on the under side of the slide 60 (Figs. 1 and 2) to hold the same in a predetermined position in the guideway, in accordance with the size of the shoe. By yieldingly mounting 20 the toe supporting rod 56 as above described, the toe of the shoe may be tipped downward against the action of the metal strip 58 when the operator is positioning the shoe. The post 62 is slidably mounted in a pedestal 67 forming 25 part of the bracket 26. Pivoted on the pedestal 67 is a spring-pressed pawl 68 which engages one of a plurality of ratchet teeth 70 (Fig. 2) on the post 62 and normally prevents downward movement of the post in the pedestal 67. The post 30 may be conveniently raised or lowered to its desired operating position by the operator.

In order to clamp the covering flap 20 (Fig. 1) against the breast of the heel 22 and usually against the rear end of the shank portion of the 35 sole of the shoe, the heel is provided with the clamping pads 52, 54 (Figs. 1, 2, 3, 4 and 6) which are preferably made of rubber or other resilient material and are arranged to engage the rear face and the covered breast of the heel respectively. The pads 52, 54 when in engagement 40 with the heel extend laterally across the same, the face of the pad 52 which engages the rear face of the heel being of suitable size and shape to accommodate a wide variety of heels. The 45 pad 52 may be readily detached from the machine and preferably three pads having differently shaped operative surfaces are provided so that a pad suitable for use in connection with any particular heel may be readily positioned in 50 the machine.

The pad 52 is held in a holder 72 by pins 73 threaded into the sides of the holder and fitting in recesses in the pad. The holder 72 has projecting from its opposite sides a pair of coaxial 55 rods 74 and 76 (Fig. 4) which are rotatably mounted in the lower ends of a pair of bell-crank-levers 78 (Figs. 1 to 4). The rod 74 at the right side of the holder, as viewed in Fig. 4, has its projecting portion covered with a rubber sleeve 75 (Figs. 3 and 4) so that the operator may conveniently grip the same with his right hand when moving the pads into their operative positions against the heel. The rod 76 (Fig. 4) at the left side of the holder has a projecting portion carrying a handhold 80 (Figs. 2, 3 and 4) through the provision of which the pad 52 may be rotated by the operator in positioning the pad against the rear face of the heel. In order to prevent idle rotating movement of the pad 52 a friction washer 82 (Fig. 4) is provided between the handhold 80 and the lower end of the corresponding bell-crank-lever 78. Rotation of the 65 handhold 80 in opposite directions is limited by faces 86 (Fig. 3) of the handhold with a pin 88 70 projecting from the adjacent bell-crank-lever 78.

The pad 54 which is forced against the flap 20 (Fig. 1) after its application to the breast of the heel by the operator, is secured in a holder 90 (Figs. 1 to 4 and 6) by pins 92 (Figs. 3 and 6) threaded into the sides of the holder and fitted 5 into recesses of the pad. The pad holder 90 is provided with a recess 94 (Figs. 3 and 6) for receiving a bar 96 having forwardly bent ends 98 which lie against opposite sides of the holder and have secured to them coaxial rods 100 (Figs. 3 10 and 6) and 102 (Fig. 6) rotatably mounted in the lower ends of a pair of bell-crank-levers 104. By pulling downward on the pad holder 90, the pad 54 may be removed from the machine and another pad of a different shape and size in a 15 similarly shaped holder may be secured in the machine by engaging the recess 94 of the holder with the bar 96 and pressing the holder upward.

The rod 100 (Fig. 6) at the right side, as viewed 20 by the operator extends beyond the adjacent arm of the bell-crank-lever 104 in which it is mounted and has on it a rubber sleeve 106 (Figs. 3 and 6) which is also gripped by the right hand of the operator when he grips the sleeve 75 (Figs. 3 and 4) mounted upon the rod 74. The rod 102 extends 25 beyond the arm of the bell-crank-lever 104 in which it is mounted and has secured to it a curved handhold 108 (Figs. 3, 4 and 6) corresponding to but larger than the handhold 80 (Figs. 3 and 4). A friction washer (not shown) 30 is provided between the handhold 108 and the adjacent bell-crank-lever 104 and a stop pin 110 (Fig. 3) carried by the bell-crank-lever is engaged 35 by faces 112 of the handhold to limit rotation of the pad 54 in the bell-crank-lever 104. The sleeves 75 and 106 and the handholds 80 and 108 are engaged by the right and left hands, respectively, of the operator preparatory to moving the pads 52, 54 into engagement with the heel of the shoe mounted upon the shoe support 32 (Figs. 1 40 and 2).

When the pads 52, 54 have been brought downward and forward to embrace the heel they are moved toward each other and are rotated by the action of the operator's hands on the rubber-covered rods 74, 100 and the handholds 80, 108, as will appear later, to insure that the pads shall engage and fit snugly against the rear ends and the flap-covered breasts of heels of the different shoes successively mounted upon the shoe support 50 32.

The bell-crank-levers 78, 104 at opposite sides of the pads 52, 54, respectively, are pivoted on a rod 114 (Figs. 1 to 4) which is carried by bifurcations 116 of a pad supporting lever or carrier 118 55 and is parallel to the rods 74, 100 of the respective pad holders 52, 54. The upper ends of the bell-crank-levers 78, 104 at each side of the pads are pivoted through rods 120 (Figs. 1, 2, 3 and 4) and 122 (Figs. 1, 2 and 3), respectively, to the 60 lower ends of a pair of toggle links or arms 124, 126 (Figs. 1 to 4) which extend upward toward each other and at their upper ends are pivoted by a rod 128 to a beam 130. The links 124, 126 may be described as constituting a toggle the 65 knuckle of which is pivoted to the beam 130 by the rod 128 and the ends of which are pivoted to the respective bell-crank-levers 78, 104. Pivoted to the beam 130 by a rod 132 is a link 134 the lower portion of which is pivoted to the 70 bifurcated portion 116 of the carrier 118 by a rod 136.

The arrangement is such that when the pads 52, 54 are pressed against the heel of a shoe upon the support 32 and the beam 130 is moved down- 75

ward, the pads are pressed bodily downward and are moved toward each other about the rod 114. Secured to the rods 120, 122 are the opposite ends of a tension spring 138 which tends normally to draw the rods together and thus to hold the pads 52, 54 apart. When the pads 52, 54 are in their respective inoperative positions shown in Fig. 2 in which they are located well above and rearward of the heel they are to engage, the tension spring 138 is expanded and the pads are separated sufficiently to enable them to pass freely in front of and behind the heel of the shoe upon the support 32 when they are moved downward by the operator into position against the work.

In positioning the pads 52, 54 against the work the operator grasps the sleeves 75, 186 with his right hand and the handholds 80, 108 with his left hand and moves the pads downward and forward toward each other until the pad 54 engages the covered breast of the heel and the rear end of the shank portion of the sole, and the pad 52 engages the rear face of the heel. In positioning the pads 52, 54 against the heel the operator usually rocks the pads slightly through the handholds 80, 108 to cause them snugly to fit the heel. During the movement of the pads 52, 54 toward each other the rod 128 connecting the toggle links 124 and 126 to each other moves downward toward the rod 114 and the rods 120, 122 move away from each other, and as the beam 130 is moved further downward through mechanism, which will be described later, to press the pads downward and toward each other against the heel, the rods 120, 122 move further away from each other. The result of the movements of the rods 120, 122 away from each other is that a greater proportion of pressure is applied lengthwise of the shoe against the heel than is applied in a downward direction as the pads 52, 54 approach more closely to each other. This result is particularly advantageous in operating upon shoes having high Louis heels the upper portions of the breasts of which are sharply convexed laterally, since it insures that the part of the breast flap near the tread end of the heel shall be forced against the breast of the heel with adequate pressure and also insures that the flap shall be effectively clamped against the lateral margins of the projecting portion of the heel breast.

Mounted for sliding movement on the beam 130 is a block 140 (Figs. 1 to 4) adjustable forward and rearward through the provision of a screw 142 which is rotatably mounted in the rear end of the beam and is threaded into a depending boss 144 (Fig. 4) of the block. As will appear later, by moving the block 140 into different operative positions along the beam 130, the proportion of lengthwise and heightwise pressures exerted by the pads against the work may be varied in accordance with the shape of the heel of the shoe. The block 140 has pivotally connected to it by pins 146 (Figs. 1 to 4) the upper ends of a pair of beam supporting links 148 (Figs. 1, 2 and 3) extending downward and forward. The lower ends of the beam supporting links 148 (Figs. 1 and 2) are pivoted through pins 150 to arms of a bifurcated pad actuating lever 152. The lever 152 is pivoted on a horizontal bearing pin 154 secured in the bracket 26, the arms of the lever converging at their lower ends into a single shank portion. A ratchet block 156 is secured to the lower end of the pad actuating lever 152, the block being curved concentrically with respect to the axis of the bearing pin 154 and being provided with ratchet teeth 158.

The carrier 118 is pivoted at its rear end upon a pin 160 mounted at the upper end of a guiding lever 162 which is pivoted on a bearing pin 164 secured to the shoe supporting bracket 26. In order normally to urge the carrier and the parts mounted thereon upward to a position in which the pads 52, 54 are located well above and rearward of the shoe support 32, there is provided a spring 166 which is coiled around the pin 160 and is of sufficient strength to overcome the weight of the carrier 118 and the parts mounted thereon. The carrier guiding lever 162 carries a roll 188 which is normally held in engagement with a stop 170 by a spring 172. With the above arrangement, when the machine is idle the pads 52, 54 are raised and moved rearward to the position shown in Fig. 2 so that the shoe on the last may be readily placed in the shoe and the breast flap may be conveniently pressed against the breast of the heel by the operator. During the downward movement of the pads 52, 54 toward the shoe the beam 130 swings about its pivotal connections to the beam supporting links 148 which swing about their pivotal connections to the pad actuating lever 152. Also, during the downward movement of the pads 52, 54, the carrier 118 swings downward about the pin 160 which is swung forward with the carrier guiding lever 162 about the bearing pin 164.

When the pads 52, 54 are being pressed against the shoe by treadle-operated mechanism, which will be described later, the ratchet teeth 158 of the block 156 are engaged by a pawl 174 which, while the pads are moved by the operator into engagement with the heel, is held away from the ratchet teeth. The pawl 174 is pivoted upon the horizontal pin 176 secured in a presser arm 178 which is pivoted on the bearing pin 154 and is arranged to be swung upward to cause, through the pawl 174, the pads 52, 54 to be pressed against the shoe. A spring-pressed plunger 180 in the presser arm 178 constantly urges the pawl 174 forward toward the ratchet teeth 158. When the presser arm is in its lowered position (Figs. 1 and 2) it engages a stop face 182 (Fig. 2) on the shoe supporting bracket 26 and the pawl 174 is held away from the ratchet teeth 158 by a pin 184 on the bracket which engages an arm 186 of the pawl. The shoe supporting bracket 26 has rotatably mounted on it a roll 188 which is engaged by the forward face of the ratchet block 154 during the upward movement of the same. The rear end of the presser arm 178 is raised by a rod 190 operated by a treadle 192 (Fig. 1) which is normally held in a raised position by a spring 194.

As the pads 52, 54 are moved downward by the operator into engagement with the heel the ratchet block 156 springs upward past but does not engage the pawl 174. When the pads 52, 54 have been positioned against the heel, the presser arm 178 is raised, the pawl 174 being moved by the plunger 180 into engagement with one of the ratchet teeth 158. Further upward movement of the presser arm 178 operated through the treadle rod 192 to the position shown in dotted lines in Fig. 1 causes the pads to be forced with considerable pressure against the heel. If desirable, the treadle rod 190 of the machine may be mechanically operated.

By moving the block 140 into different adjusted positions along the beam 130 it is possible to vary the proportion of inward pressure of squeeze of the pads 52, 54 against the heel with relation to the downward pressure of the pads against the

heel. The pads 52, 54 are moved bodily downward about the pin 160 at the lower end of the carrier 118, which pin is located rearward of the rods 114 and is effected by a downward pull of 5 the beam supporting links 148. Assuming therefore, that the pull on the beam supporting links 148 is constant, forward adjustment of the block 140 on the beam 130 increases owing to increased leverage or downward pressure of the pads against 10 the work, and rearward adjustment of the block 140 on the beam decreases said leverage. The inward pressure of the pads 52, 54 is obtained by moving the beam downwardly about its forward end which is connected by the link 134 to 15 the forward end of the carrier 118. If the block 140 is moved near to the pivot rod 128, the inward pressure of the pads 52, 54 against the shoe, assuming a constant pull on the beam supporting links 148 is maintained, is by the change 20 in leverage decreased, and if the block 140 is moved into a rearward adjusted position on the beam 130, the inward pressure of the pads is increased. Accordingly, forward adjustment of the block 140 on the beam 130 increases the downward 25 pressure and decreases the inward pressure of the pads against the heel and vice versa. By varying the amount of inward pressure the pressure of the pad against the heel may be quickly varied by the operator in accordance with the 30 shape of the breast of any heel.

The operator releases the treadle 192 as soon as the heel has been securely clamped by the pads 52, 54, the clamping pressure of the pads against the heel being maintained until the glue has 35 dried, through the provision of latching mechanism which is best shown in Figs. 7 and 8, and comprises a pawl 196 (Figs. 1, 2, 7 and 8) for engaging and holding the ratchet teeth 158 and holding the lever 152 and the pads in their raised 40 clamped positions against the heel. The locking pawl 196 is pivoted at the forward end of a pawl carrying arm 198 (Figs. 7 and 8) by a pin 200 (Figs. 1, 7 and 8). The pawl carrying arm 198 extends downward and rearward and is pivoted 45 at its rear end on a bearing pin 202 (Figs. 1, 2, 3 and 4) secured to a bracket 204 fixed to the main frame. The pawl 196 is normally forced against the ratchet teeth 158 by a spring-pressed plunger 206 (Figs. 7 and 8) carried by the arm 198. Pivoted upon the pin 200 on which the pawl 196 is mounted is an upper toggle link 208 the lower end of which is pivoted to a lower toggle link 210. The lower end of the toggle link 210 is keyed to a shaft 212 mounted in the bracket 204. 50 The shaft 212 to which the lower toggle link 210 is secured has fixed on it a rearwardly extending arm 214 (Figs. 1, 7 and 8) to which is connected a spring 216 extending upward and having its upper end connected to a pin 218 secured to the 55 bracket 204. The spring 216 tends to hold the toggle links 208, 210 in their straightened positions shown in Fig. 7 and therefore in cooperation with the spring-pressed plunger 206 to hold the pawl 196 in engagement with the ratchet teeth 158.

In order to release the pads 52, 54 preparatory to removing the shoe from the machine after the flap attaching adhesive has dried, there is provided a hand lever 220 (Figs. 1 and 2) connected 60 by a rod 222 (Figs. 1, 2, 7 and 8) to an arm 224 pivoted upon the shaft 212 to which the toggle link 210 is secured. A flange 226 (Figs. 1, 7 and 8) of the arm 224 is positioned behind an extension 228 of the lower toggle link 210, the arrangement being such that when the hand lever 75

220 is pulled upward the then straightened toggle is broken and the pawl 196 is withdrawn from the ratchet teeth 158 so that the pads 52, 54 are released from the heel and are moved upward and rearward by the springs 166 and 172. 5

As the toggle is broken as above described, pressure of the pads 52, 54 against the heel is gradually relieved through the provision of the spring 216 which tends to straighten the toggle. The gradual relieving of the pressure of the pads 52, 54 against the heel prevents shock and noise which would otherwise occur were the pawl 196 suddenly withdrawn from the ratchet teeth 158 while the pads 52, 54 are pressed against the heel. When the pawl has been lowered far enough entirely to relieve or substantially relieve the pressure of the pads 52, 54 against the heel, a cam face 230 (Figs. 7 and 8) on the pawl 196 engages a cam roll 232 carried by the bracket 204. The pawl 196 during its continued downward movement is moved away from the ratchet teeth 158 by the cam roll 232. After the operator releases the hand lever 220 it drops to its lower position and the toggle is again straightened out under the action of the spring 216 to force the pawl 196 against the ratchet teeth 158, as best shown in Fig. 7. 15 20 25

If desirable, a plurality of heel clamping units, for example twelve, such as above described, may be mounted upon a turret 234 (Figs. 9 and 10) which is secured to a rotatable drive sleeve 236 (Fig. 9) mounted upon bearings (not shown) supported by the frame of the machine. The work-supporting bracket 26 of each of the units may be secured to the turret by screws 238 (Figs. 9 and 10), and the presser arm 178 may be raised by a cam 240 which is mounted upon ball bearings 242 (Fig. 9) secured to a cylindrical casing 244. Threaded into the upper end of the cylindrical casing 244 is a screw 246. A thick rod 248 is rigidly fixed to the frame of the machine and extends upward through a recess in the screw 246, and surrounding the rod is a vertically slideable sleeve 250 having at its upper end a flange 252 engaged by a strong spring 254 which surrounds the rod 248 and has its upper end in engagement with the screw 246. The screw 246 may be moved into different adjusted positions in the cylindrical casing 244 to vary the compression of the spring 254. With the above arrangement it will be clear that when the sleeve 250 is moved upward the screw 246 is also forced upward with yielding pressure through the spring 254 and carries with it the cylindrical casing 244 and the cam 240. 30 35 40 45 50 55

Mounted in the lower part of the machine frame is mechanism for indexing the turret 234 step by step about an axis 256 and for raising and lowering the sleeve 250. In accordance with the preferred practice, after the operator has positioned the pads 52, 54 of one of the units in the loading position (Fig. 9) against the heel by hand as above described, the sleeve 250 is raised manually through suitable mechanism by depressing a treadle (not shown) to force the pads 52, 54 securely against the heel. Upon continued depression of the treadle, a clutch (not shown) is tripped, the arrangement being such that after the clutch has been tripped the turret is indexed through $\frac{1}{2}$ of a revolution and the sleeve 250, 70 during such indexing movement, is moved upward under mechanical pressure to force the pads 52, 54 with additional pressure against the heel.

When the unit in which the shoe is to be positioned is in the loading station (Fig. 9), the 75

presser arm 178 is positioned above a face 258 of the cam 240. Since the arm 178 is forced upward by the cam 240 during the indexing of the turret through the first $\frac{1}{2}$ of a revolution, it is 5 desirable that the cam 240 swing with the turret to the first indexed position. Accordingly, the cam 240, when forced against the operating arm 178, rotates with the arm to the first indexed position, and when the sleeve 258 is lowered, causing 10 through the above-described mechanism the cam 240 to be moved to its lowered inoperative position, the cam swings back to its original position under the action of a spring 260 (Fig. 10), the retractive movement of the cam under the 15 action of the spring being limited by a depending tongue 262 which extends downward from the cylindrical casing 244 into a recess 264 of the cam.

The turret is also provided with a cam 266 20 (Fig. 11) which corresponds to the stop 170 of the single unit and is engaged during the rotation of the turret 234 by the rollers 168 of the respective units when there are no shoes in said units. The cam 266 is provided with a cylindrical face 268 which is concentric with the axis 256, and a recess 270 arranged at the loading station for allowing the pads 52, 54 of the unit located at said station to be moved well back from the shoe support 32 so as to provide ample space 25 for the operator to lay the breast flap against the heel and to beat it into position by a hand tool. If the shoe supports leave the loading position without shoes on them and these pads are therefore in their raised positions shown in Fig. 2, the 30 cylindrical surface 268 of the cam 266 moves the pads somewhat forward, that is, away from the axis 256 of rotation of the turret 234, and prevents the units from fouling each other. If the clamping units are all loaded and the pads 52, 40 54 are clamped against the heels of the shoes in the respective units, the rollers 168 will be out of engagement with the cam 266.

Each of the units of the turret machine is provided with a locking pawl 272 which is similar to the above-described pawl 196 and is automatically operated to release the work just before the unit arrives at the loading station. Since the parts of the above-described locking unit are substantially identical with corresponding parts of the 50 unit disclosed in Figs. 7 and 8, the above-described parts have been given, respectively, the same numerals each followed by the letter *a*. The pawl 272 is normally held out of engagement with the teeth 158 of the ratchet block 156 against the action of the spring-pressed plunger 206*a* by a latch 274 having at its upper end a hook 276 arranged to engage a shoulder 278 on the pawl 272. As soon as the shoe support begins to move toward the loading station, the inner end of the latch 274 engages beneath a cam 280 secured by screws 282 to the main frame of the machine. The cam 280 causes the hook 276 on the latch 274 to be raised from engagement with the pawl 272 to allow the pawl to be moved by the spring-pressed plunger 206*a* into engagement with the ratchet teeth 158, any movement of the ratchet block 156 when the power squeeze is applied causing the ratchet teeth to slip past the pawl. The latch 274 is pivoted at 284 to the rear end of 60 one arm of a bell-crank-lever 286 which is pivoted on the pin 200*a*. The bell-crank-lever 286 has a downwardly and forwardly extending arm which has formed in it a slot 288 extending along said arm, the slot engaging a pin 290 extending from the bracket 204*a*. The pivot con-

nected the upper and lower toggle links 208*a*, 210*a*, has pivoted on it the forward end of a link 292 which at its rear end is pivoted to one arm of a bell-crank-lever 294 pivoted on a horizontal shaft 296 secured to the bracket 204*a*. The other arm of the bell-crank-lever 294 has a cam roll 298 which is arranged to engage a cam groove 300 of a cam 302 secured to the frame of the machine as the unit moves from its eleventh indexed position to the loading station. When 10 the shoe support and the clamping mechanism of one of the units is about to leave the eleventh station around the machine, the toggle is straightened and the toggle 272 is holding the pads 52, 54 pressed against the heel. As the unit 15 is moving from its eleventh indexed position to the loading station, the cam 298 engages the cam groove 300 in the fixed cam 302 and is moved downward. As the cam roll 298 is moved downward, the bell-crank-lever 294 is swung in a 20 direction to break the toggle and, since the lower end of the lower toggle link 210*a* is pivoted in the bracket 204*a*, the upper toggle is moved downward while the pawl 272 is still in engagement with the ratchet teeth 158 on the block, 25 the cam being so shaped that the toggle is gradually broken and pressure of the pads 52, 54 against the heel is gradually relieved. As above stated, the gradual relieving of the pressure prevents the shock and noise which might occur 30 were the pawls 272 suddenly withdrawn from the ratchet teeth 158. When the pawl 272 has been lowered far enough to substantially relieve the pressure of the pads 52, 54 against the heel, the cam face 232*a* of the pawl engages the cam roll 335 232*a* carried by the bracket, moving the pawl rearward away from the ratchet teeth 158. During this movement the hook 276 at the forward end of the ratchet 274, which has been moved downward by the pawl 272, engages the shoulder 40 278 on the pawl and holds the same in its rearward position away from the ratchet teeth 158. Just before the unit arrives at the loading station, the cam roll 298 on the bell-crank-lever 294 leaves the cam 302 and the spring 216*a* which 45 tends to hold the toggle links 208*a*, 210*a* in a straightened position, straightens the links and raises the pawl, as illustrated in Fig. 9, in readiness for it to be moved into engagement with the ratchet teeth 158 when the unit again leaves the 50 loading station. By providing the latch 274 the pawl 272 is not moved into engagement with the ratchet teeth 158 until the block 156 has been swung to approximately its raised position.

Having described our invention, what we claim 55 as new and desire to secure by Letters Patent of the United States is:

1. A machine for clamping a covering flap against the breast of an attached heel of a shoe having, in combination, a support for the shoe, 60 a resilient pad, mechanism for moving the pad heightwise of the shoe against the breast of the attached heel of the shoe to clamp the flap against the heel breast, mechanism responsive to heightwise pressure of the pad against the heel breast for moving the pad lengthwise of the shoe against the heel breast, and means for varying the degree of lengthwise thrust of the pad against the heel breast with relation to the heightwise thrust of the pad against the heel breast in accordance 65 with the shape of the heel of the shoe.

2. A machine for clamping a covering flap against the breast of an attached heel of a shoe having, in combination, a support for the shoe, a pair of resilient pads, means constructed and 70

arranged to move the pads heightwise of the shoe to press the respective pads against the breast and the rear face of the heel, said means also being constructed and arranged to move the 5 pads toward each other to exert pressure against the heel in directions lengthwise of the heel, and means for varying the degree of lengthwise pressure of the pads against the heel with relation to the heightwise pressure of the pads against 10 the heel in accordance with the shape of the heel of the shoe.

3. A machine for clamping a covering flap against the breast of an attached heel of a shoe having, in combination, a support for the shoe, a 15 pair of pads, means for moving the pads heightwise of the heel to exert a thrust against the breast and the rear face of the heel, means for moving the pads toward each other when they are moved heightwise against the heel to exert 20 a thrust lengthwise of the heel against the breast and the rear face of the heel, and means for varying the thrust of the pads lengthwise against the heel with relation to the thrust of the pads heightwise against the heel in accordance with 25 the shape of the heel of the shoe.

4. A machine for clamping a covering flap against the breast of an attached heel of a shoe having, in combination, a support for the shoe, a pair of rubber pads, a spring for normally urging 30 the pads away from each other, and means for moving the pads heightwise of the heel to exert a thrust against the breast and the rear face of the heel, said means comprising a toggle through which the pads are moved toward each 35 other against the action of the spring when the pads are moved heightwise against the heel thereby exerting a thrust lengthwise against the breast and the rear face of the heel.

5. A machine for clamping a covering flap 40 against the breast of an attached heel of a shoe having, in combination, a support for the shoe, a carrier, levers pivoted to said carrier, heel-engaging pads mounted upon the respective levers, a toggle the knuckle of which is pivoted to 45 the carrier and the opposite ends of which are pivoted to the respective levers, and means operating through the toggle constructed and arranged to move the pads as a unit against the breast and the rear face respectively of the heel 50 of the shoe and then to swing the pads toward each other with relation to the carrier as pressure is exerted by the pads against the shoe.

6. A machine for clamping a covering flap 55 against the breast of an attached heel of a shoe having, in combination, a support for the shoe, a carrier, a beam, a link for pivotally connecting the beam to the carrier, bell-crank-levers pivoted to the carrier, heel-engaging pads pivoted to the 60 respective bell-crank-levers, a toggle the knuckle 65 of which is pivoted to the beam and the ends of which are pivoted to the respective bell-crank-levers, said beam being movable about spaced pivots to enable the operator to move the respective pads against the breast and the rear face of 70 the heel of the shoe from an inoperative position remote from the heel, and operating means connected to the beam constructed and arranged first to move the carrier about one of said pivots for forcing the pads against the breast and the rear 75 face respectively of the heel and then to swing the bell-crank-levers with relation to the carrier thereby moving the pads toward each other to press the heel between them.

7. A machine for clamping a covering flap 75 against the breast of an attached heel of a shoe

having, in combination, a support for the shoe, a carrier, bell-crank-levers pivoted to the carrier, heel-engaging pads pivoted to the respective bell-crank-levers, a beam, a link operatively connecting the beam to the carrier, a toggle which is normally broken and comprises links the adjacent 5 ends of which are pivoted to the beam and the other ends of which are pivoted to the respective bell-crank-levers, said carrier being movable about spaced pivots to enable the operator to 10 move the pads into engagement with the breast and the rear face respectively of the heel of the shoe from their inoperative positions remote from the shoe, and an operating member connected to the beam for forcing the pads as a unit through 15 the broken toggle against the heel and for closing the toggle when the pads have been forced against the heel thereby swinging the pads toward each other.

8. A machine for clamping a covering flap 20 against the breast of an attached heel of a shoe having, in combination, a support for the shoe, a pair of resilient pads, means constructed and arranged to move the pads heightwise of the shoe to press the respective pads against the breast 25 and rear face of the heel, means responsive to the heightwise pressure of the pads against the heel for forcing the pads toward each other to exert pressure against the heel in directions lengthwise of the heel, and means for varying 30 the degree of lengthwise pressure of the pads against the heel with relation to the heightwise pressure of the pads against the heel in accordance with the shape of the heel of the shoe.

9. A machine for clamping a covering flap 35 against the breast of an attached heel of a shoe having, in combination, a support for the shoe, a carrier, pairs of levers pivoted to the carrier, heel-engaging pads supported by the respective 40 pairs of levers, a beam, link connections between the carrier and the beam, one or more toggles connecting the levers to the beam, a spring for normally urging the pads away from each other, and an operating link pivoted to the beam for moving the pads toward the shoe upper and for moving the pads toward each other against the 45 action of the spring.

10. A machine for clamping a covering flap 50 against the breast of an attached heel of a shoe having, in combination, a support for the shoe, a carrier, pairs of bell-crank-levers pivoted to the carrier, pads pivoted to the respective pairs of levers, a beam, link connections between the beam and the carrier, one or more pairs of toggles operatively connecting the levers to the beam, a spring for normally urging the pads away 55 from each other, said carrier being freely movable to enable the operator to move the pads into engagement with the breast and the rear face respectively of the heel of the shoe from their inoperative positions remote from the shoe, and means for operating the beam to move the pads which are in engagement with the heel toward the upper of the shoe as a unit and also to move the pads toward each other.

11. A machine for clamping a covering flap 60 against the breast of an attached heel of a shoe having, in combination, a support for the shoe, a pair of pads mounted and arranged to be moved by the operator into engagement with the breast 70 and the rear face respectively of the heel of the shoe, means for moving the pads in engagement with the heel heightwise of the shoe to force said pads with considerable pressure against the breast and the rear face respectively of the heel, 75

means responsive to heightwise pressure of the pads against the shoe for moving the pads toward each other lengthwise of the shoe, and means for varying the degree of lengthwise pressure of the pads against the heel with relation to the degree of heightwise pressure of the pad against the heel in accordance with the shape of the heel of the shoe.

12. A machine for clamping a covering flap against the breast of an attached heel of a shoe having, in combination, a support for the shoe, a carrier, pairs of bell-crank-levers pivoted to the carrier about a common axis, a pair of heel-engaging pads pivoted to corresponding pairs of levers, a beam, a link connection between the carrier and the beam, one or more toggles connecting the levers to the beam, a spring for urging the pads away from each other, a guiding lever mounted on a fixed pivot, said carrier being pivoted to the guiding lever to enable the operator to move the pads into engagement with the breast and the rear face respectively of the heel from their inoperative positions remote from the shoe support, means for constantly urging the carrier and the guiding lever toward their inoperative positions away from the shoe support, a stop for limiting movement of the guiding lever away from the shoe support under the action of said means, and an operating link pivoted to the beam for moving the pads in engagement with the heel toward the shoe upper and toward each other.

13. A machine for clamping a covering flap against the breast of the attached heel of a shoe having, in combination, a support for the shoe, a pair of pads, means constructed and arranged to enable the operator to move the pads into engagement with the breast and the rear face respectively of the heel of the shoe from their inoperative positions remote from the shoe upon the support, pad-operating mechanism comprising a ratchet which is moved to a predetermined position when the pads are in engagement with the heel, a presser arm, a pawl carried by the presser arm, a spring for urging the pawl toward the ratchet, a stop, a pin for holding the pawl away from the ratchet against the action of the spring when the presser arm is in engagement with the stop, and means for operating the presser arm to move the same away from the stop thereby permitting the pawl to be moved into engagement with said ratchet under the action of the spring and then causing the pad-operating mechanism to force the pads against the heel.

14. A machine for clamping a covering flap against the breast of an attached heel of a shoe having, in combination, a support for the shoe, a pair of resilient pads, pad-supporting means comprising a carrier, a guiding lever pivoted at one end to the machine frame and at the other end to the carrier to enable the operator to move the respective pads into engagement with the breast and the rear face of the heel of the shoe from their inoperative positions remote from the shoe, springs for normally moving the carrier and the guiding lever away from the shoe support to move the pads to and hold the same in their inoperative positions when the machine is idle, means connected to the carrier for forcing the pads with considerable pressure against the breast and the rear face respectively of the heel, and means for retaining the pads in clamped relation with the heel.

15. A machine for clamping a covering flap against the breast of an attached heel of a shoe having, in combination, a plurality of clamping units, a rotatable turret upon which said units are mounted, said turret being mounted for step by step rotation to move the clamping units successively in a closed path to and from a loading station, each of said clamping units comprising a support for a shoe, a pair of resilient pads, mechanism comprising a presser arm constructed and arranged to move the pads heightwise of the shoe against the breast and rear face respectively of the heel of the shoe and to swing the pads toward each other, and a latch for retaining the pads in clamped relation with the shoe, a cam constructed and arranged to operate the presser arms of the successive clamping units in the loading station to cause the pads of the units to be forced against the heels of the shoes in the respective units, and a cam for releasing the latches of the successive units just before they arrived at the loading station.

16. A machine for clamping a covering flap against the breast of an attached heel of a shoe having, in combination, a carrier, pairs of levers pivoted to the carrier, holders pivoted to corresponding pairs of levers, resilient pads secured to the respective holders, friction washers for preventing the holders from turning idly in the corresponding pairs of levers, and handholds connected to the respective pad holders for rotating the pads into predetermined positions with relation to the respective levers.

WILLIAM NEIL BRAY.
